UNITED STATES PATENT OFFICE.

JOHN M. LEVIER, OF CLARKSBURG, WEST VIRGINIA.

METALLIC RAILWAY-TIE.

1,001,055.

Specification of Letters Patent. Patented Aug. 22, 1911.

Application filed May 1, 1911. Serial No. 624,338.

To all whom it may concern:

Be it known that I, JOHN M. LEVIER, a citizen of the United States, residing at Clarksburg, in the county of Harrison and State of West Virginia, have invented a new and useful Metallic Railway-Tie, of which the following is a specification.

This invention relates to metallic railway ties and its principal object is to provide a tie of this character capable of yielding when subjected to the weight of a car so as to thus cushion the rails and render the track as elastic as where ordinary wooden ties are employed.

15 A further object is to provide a tie of this type which is formed of but few parts and which can be readily constructed.

A further object is to provide improved means for securing rails to the tie.

20 With the foregoing and other objects in view which will appear as the description proceeds, the invention resides in the combination and arrangement of parts and in the details of construction hereinafter described

25 and claimed, it being understood that changes in the precise embodiment of the invention herein disclosed can be made within the scope of what is claimed without departing from the spirit of the invention.

30 In the accompanying drawings, the preferred form of the invention has been shown.

In said drawings, Figure 1 is a plan view of a tie embodying the present improvements. Fig. 2 is a longitudinal section therethrough. Fig. 3 is an enlarged transverse section through the tie.

Referring to the figures by characters of reference 1 designates the base member of the tie, the same being preferably formed of

40 heavy sheet metal provided with upstanding longitudinal folds 2 coöperating with the base to form a central longitudinal channel 3.

A transversely extending supporting rib 4 is formed within each end portion of the

45 channel 3 and tongues 5 extend from the ends of the base member and are arranged close to these ribs 4. Another stop rib 6 is arranged transversely within the central portion of the channel. Transverse corrugations 7 may be formed at any points desired upon the bottom of the base member,

50 these corrugations serving to engage the road bed and thus hold the tie against creeping.

55 The top member 8 of the tie is preferably formed of a metal bar similar in contour

to an ordinary railroad rail, the base flanges 9 of this member being disposed between the upstanding portions 2 of the base member while the head of the bar projects above said 60 upstanding portions 2 and has rail receiving recesses 10 in the upper portion thereof and at proper distances apart, one wall of each of these recesses overhanging the bottom thereof as shown at 11 so as to engage one 65 of the base flanges of the rail 12 supported by the tie. The end portions of the bar 8 are designed to bear on the ribs 4 and as these ribs are higher than the stop rib 6, it will be apparent that the middle portion 70 of the member 8 is normally spaced from the rib 6.

Tongues 13 extend from the ends of the member 8 and are designed to fit snugly upon the tongues 5, bolts 14 or the like being utilized for the purpose of securing the tongues together and thus holding the two members 8 and 1 against displacement relative to each other.

The head portion of the member 8 is preferably thickened under the recesses 10, as indicated at 15, thus reinforcing the tie at these points where the greatest strain is received.

Pivottally connected to the member 8 adjacent each recess 10 is a jaw 16 having an arm 17 extending therefrom and designed to swing upwardly above the top face of the member 8.

In using the tie, the rails to be fastened are inserted into the recesses 10 so that one base flange of each rail will be lapped by the overhanging wall of the recess in which the rail is seated. In order to facilitate the insertion of the rails into the recesses, one 95 wall of each recess is preferably inclined as shown at 18. After the rails have been properly seated, the jaws 16 are swung into engagement with the other base flanges of the rails and the arms 17 are hammered 100 across the top of the tie member 8 and then forced in the direction of the engaged rail so as to cause the jaw to bind tightly upon the adjacent rail, it being understood that the arm, by lapping the member 8, will hold 105 the jaw against displacement relative to the rail.

When a load is applied to the rail 12, the tie member 8 will yield so as to thus cushion the rails, this yielding action continuing 110 until the middle portion of the member 8 contacts with the rib 6. Any further yield-

ing of the upper member 8 will occur between the ends of the member 8 and the rib 6 but it is to be understood that such additional yielding will only take place when 5 the tie is subjected to a load far in excess of that ordinarily contemplated.

It will be apparent that a tie such as described can be manufactured at comparatively slight cost and although formed entirely 10 of metal will have all of the yielding qualities of an ordinary wooden tie.

As shown in the drawings the jaws 16 are arranged at the same sides of the openings in the tie. In building a track, therefore, 15 it has been found desirable to arrange each tie oppositely to the adjoining ones so that the jaws on one tie will engage the right hand base flanges of the rails while the jaws on the next succeeding tie will engage 20 the flanges at the left sides of the rails. The rails will thus be firmly anchored to the ties and spreading thereof will be positively prevented.

What is claimed is:—

- 25 1. A metallic railway tie including a base member having upstanding terminal portions, and a top member secured at its ends upon said upstanding portions.
- 30 2. A metallic railway tie including a base member, a top member bearing solely at its ends upon the base member, there being a continuous space between said bearing portions, and a stop element upon the base member and adjacent the center thereof.
- 35 3. A metallic railway tie including a base member having a longitudinal channel, a top member yieldably mounted within the channel and supported solely at its ends by the base member, and means upon the base

member for limiting the yielding action of 40 the top member.

4. A metallic railway tie including a channeled base member, a top member yieldingly mounted therein and supported solely at its ends by the base member, and means 45 upon the top member remote from the ends thereof for engaging rails.

5. A metallic railway tie including a yieldable rail supporting member, non-yielding supports for the end portions thereof, and means below the member for limiting the yielding movement thereof. 50

6. A metallic railway tie including a yielding rail supporting member, non-yielding supports for the end portions thereof, said member having a rail receiving recess therein, one wall of the recess being inclined to lap and engage a flange of the rail, a rail engaging member pivotally mounted adjacent the recess, and means on 55 said member for engaging the tie to hold the member in engagement with the rail. 60

7. In a metallic railway tie, the combination with a rail supporting member having a rail receiving recess, one wall of the recess being inclined to lap and engage a flange of the rail, of a rail engaging jaw pivotally connected to said member, and means integral with said jaw and bendable into engagement with said member to hold the jaw 65 in engagement with a flange of the rail. 70

In testimony that I claim the foregoing as my own, I have hereto affixed my signature in the presence of two witnesses.

JOHN M. LEVIER.
